ABSTRACT OF THE DISCLOSURE

A latch device of the kind intended to retain a resiliently loaded member in a first position, the latch device comprising a first member which extends into the path of the member, a second member telescopically engaged with the member, and movable between first and second axial positions, the arrangement being that as the member is moved from its first to its second position the member will telescope relative to the member and as the latter is returned to its first position the friction between the two members will cause the member to be moved out of engagement with the resiliently loaded member.

This invention relates to latch devices of the kind intended to retain a resiliently loaded member in a first position, the latch device when operated serving to permit said member to move to a second position under the action of its resilient loading.

The object of the invention is to provide such a latch in a simple and convenient form.

According to the invention a latch device of the kind specified comprises a first member extending into the path of said resiliently loaded member, a second member telescopically engaged with said first member and movable between first and second axial positions, the arrangement being such that as the second member is moved from its first to its second position the first member will telescope relative to the second member and as the latter is returned to its first position the friction between the two members will cause the first member to be moved out of engagement with the resiliently loaded member thereby allowing the latter to move to its second position.

In the accompanying drawings:

FIGS. 1 and 2 illustrate in sectional side elevation, two examples of latch devices in accordance with the invention. The latch devices therein illustrated are intended to control the setting of the fuel control rod of a liquid fuel pumping apparatus. The fuel control rod is indicated at 10 in the drawings and as shown particularly in FIG. 1 it is resiliently loaded by means of a coiled compression spring 11 in the direction to increase the quantity of fuel which is supplied by the apparatus. In this position shown the control rod is set to provide the normal maximum quantity of fuel. For starting purposes it is well known that an excess of fuel is required but it is essential to ensure that this excess should not be obtainable by the driver of the vehicle when the vehicle is in normal use.

Referring now to FIG. 1 the latch device comprises a first member 12 which is of stepped cylindrical form. The narrower end portion of this member extends through an

2

aperture formed in the body of the device and into the path of the free end of the fuel control rod 10. The first member is accommodated with a small degree of clearance within a bore formed in a second member 13 slideable in the body part of the device. The second member is loaded in an outward direction towards a first position, by means of a coiled compression spring 14 and acting intermediate the first and second members is a light coiled compression spring 15. In the position shown in FIG. 1 the control rod 10 applies a force to the member 12 to cause the latter to tilt within the bore of the member 13. When excess fuel is required the member 13 is moved to a second position against the action of the springs 14 and 15 and when it is allowed to return to its first position under the action of the spring 14 the friction developed primarily at the two points of contact of the members 13 and 12 is sufficient to cause the member 12 to follow the movement of the member 13. When this occurs the narrower end of the member 12 is moved out of the path of the control rod 10 and the latter moves under the influence of its spring 11 to a position in which an excess of fuel is supplied to the engine and with the end of the member 12 bearing on this side of the rod.

When the associated engine has been started the governor of the pumping apparatus will move the control rod 10 to reduce the quantity of fuel supplied to the engine. As soon as this occurs the member 12 is moved by the light spring 15 to a position to block movement of the control rod to the excess fuel position. The operating 30 knob of the member 13 is out of the reach of the operator of the vehicle and therefore when the vehicle is in use on the road it is impossible to actuate the device to obtain an excess of fuel.

A modified form of the device is seen in FIG. 2 and parts having the same function are provided with the same reference numerals. It will be apparent that the spring 14 has been omitted so that the member must be moved by hand to its first position. It will be seen also that the body portion 16 of the device is adjustably mounted relative to the body of the pumping apparatus and in this manner variations of the setting of the control rod in the maximum fuel position can be obtained. In addition it will be noted that a stop 17 is provided and adjustment of this stop enables the position of the control rod 10 in the excess fuel position to be adjusted.

It will be appreciated that when the engine has started even if the operating knob of the member 13 is held in its innermost position then excess fuel will not be obtained once the control rod 10 has been moved out of the path of the member 12 since the latter will immediately assume its blocking position to prevent further supply of excess fuel.

Having thus described my invention what I claim as new and desire to secure by Letters Patent is:

55 1. A latch device of the kind intended to retain a resiliently loaded member in a first position, the latch device when operated serving to permit said member to move to a second position under the action of its resilient loading, the device comprising a first member extending into the path of said resiliently loaded member, a second member telescopically engaged with said first member and movable between first and second axial positions, the arrangement being such that as the second member is moved from its

first to its second position the first member will telescope relative to the second member and as the latter is returned to its first position the friction between the two members will cause the first member to be moved out of engagement with the resiliently loaded member thereby allowing the latter to move to its second position.

2. A latch device as claimed in claim 1 including resilient means acting between the members in a direction to urge the members apart.

3. A latch device as claimed in claim 2 including further resilient means acting to urge the second member towards its first position.

4. A latch device as claimed in claim 2 including adjustable stop means whereby the second position of the resiliently loaded member can be adjusted.

5. A latch device as claimed in claim 4 including means for adjusting the position of the first and second members relative to a body mounting said resiliently loaded member whereby the first position of the resiliently loaded member can be adjusted.
